UNITED STATES PATENT OFFICE.

IRVING E. BROWN, OF PROVIDENCE, RHODE ISLAND, ASSIGNOR TO THE PROVIDENCE GAS BURNER COMPANY, OF SAME PLACE.

DESIGN FOR A CONTACT-BASE FOR INCANDESCENT LAMPS.

SPECIFICATION forming part of Design No. 34,173, dated March 5, 1901.

Application filed February 7, 1901. Serial No. 46,445. Term of patent 14 years.

To all whom it may concern:

Be it known that I, IRVING E. BROWN, a citizen of the United States, residing at Providence, in the county of Providence and State 5 of Rhode Island, have invented and produced a new and original Design for the Contact-Base of Incandescent Lamps, of which the following is a specification, reference being had to the accompanying drawings, forming 10 part thereof.

This invention has reference to the base forming the end of an incandescent lamp in which the terminals of the lamp-filament are supported.

15 Figure 1 is a perspective view of the base of an incandescent lamp, showing my new design. Fig. 2 is a plan view of the contact end of the base. Fig. 3 is a plan view of the socket end of the base. Fig. 4 is a sectional view on 20 the line A A of Fig. 3.

As shown in the drawings, the leading and material feature of my design consists in the

tubular cup-shaped form of the base, the bottom *a* of which has the projecting annular ring *b*, the central opening *c*, and the openings *d d*, extending through part of the inner portion of the annular ring *b*. Recesses *d' d'* are formed around the openings *d d* and a square recess *c'* around the central opening *c* on the inner side of the bottom *a*. The annular end of the cylindrical portion *e* of the base is rounded.

Having thus described my invention, what I claim as new, and desire to secure by Letters Patent, is—

25 The design for the contact-base of incandescent lamps as herein shown and described.

In testimony whereof I have signed my name to this specification in the presence of two subscribing witnesses.

30 IRVING E. BROWN.
